CATHODE LINE CONNECTOR SYSTEM

James Henry Nye, Jackson Heights, N. Y., assignor to Federal Telephone and Radio Corporation, New York, N. Y., a corporation of Delaware

Application January 31, 1944, Serial No. 520,571.

9 Claims. (Cl. 315—39)

1

This invention relates to resonant line oscillators wherein the dual conductors are shielded and employ means for tuning the lines to the desired frequency.

Heretofore, one of the means of tuning transmission line circuits coupled to line sections mounted within a closed envelope (for example for tuning cathode filaments) was to place a short circuiting bar across the two conductors of the transmission line and slide the bar toward or away from the envelope until the desired frequency has been reached. This is generally at approximately a quarter wavelength from the end of the line section. This type of shorting means has been found to be efficient for ordinary frequencies where a quarter wavelength of the frequency is a considerable distance from the end of the line section to the shorting bar. In vacuum tubes operating at ultra high frequencies the distance from the internal end of the filament becomes considerably shortened so that the length of the cathode filament may approach a quarter wavelength in itself. With the types of couplings now in use, it is quite difficult to bring the shorting bar to within a quarter wavelength of the end of the cathode filament, therefore, an odd multiple of a quarter wavelength must be employed. This is undesirable as it lengthens the structure to a prohibitive degree.

One of the objects of my invention is to provide means whereby an effective short circuit for tuning a partially enclosed line section to resonance may be made substantially at the point at which the line section extends from the envelope.

Another object of my invention is to provide means whereby the tuning short circuit for a vacuum tube filament line may be brought into close proximity to the tube, whereby tuning of the filament line to an ultra high frequency at which the filament and internal leads are substantially a quarter wavelength long can be attained.

A further object of my invention is to provide means whereby a tube may be readily connected to and disconnected from the shielded resonant line.

Further and ancillary objects of my invention will become apparent in the following description and drawings, wherein:

Fig. 1 is a front elevational view partly in section of a vacuum tube coupled to a shielded resonant line oscillator and embodying the principles of my invention;

Fig. 2 is a horizontal sectional view taken along the lines 2—2 of Fig. 1;

2

Fig. 3 is a partial vertical sectional view taken along the lines 3—3 of Fig. 1; and

Fig. 4 is a schematic diagram of the electrical circuit employed in Figs. 1, 2 and 3.

- 5 Referring to Fig. 1, there is illustrated a vacuum tube 1, of the type employing the usual cathode 2, grid 3 and anode 4; wherein the cathode 2 of this tube is provided with a filament 2a, a pair of filament leads 5 and 6 forming a two conductor line element within the tube and a third or neutral lead 7. All three of these leads extend through and beyond the envelope and are sealed near their remote ends. The central or neutral lead 7 is secured to the lower end of the cathode filament and is employed both as a centering rod and ground connection. The remote ends of these three leads 5, 6 and 7 extending beyond the sealing means of the tube project into the adjacent end of the oscillator.
- 10 20 Each of these cathode leads are provided with flanged slip bushings 8; 9 and 10; held in frictional engagement thereto by slotted cylindrical portions 8a, 9a and 10a, and having flanged bases 8b, 9b and 10b of a greater diameter than the cylindrical portions and adapted to rest upon the lead sealing means of the envelope of tube 1. A two-conductor shielded line 30 having shielded conductors 20 and 21 is connected to the tube 1. Secured to the ends of each of the shielded conductors 20 and 21, by soldering or brazing, are cylindrical couplings 22 and 23 adapted to be slipped upon and surround the bushings 8 and 9 and secured in place against any accidental longitudinal movement by the set screws 24 and 25.
- 15 30 35 Secured to the inner periphery of the shield 20, and insulated therefrom by a thin sheet of mica, are a pair of contact springs 31 and 32, the bifurcated ends of which surround the cylindrical portions 8a and 9a and also bear down 40 with a definite amount of pressure upon the upper surface of the flanges 8b and 9b to not only assist in holding the bushings against the lead sealing heads of the tube, but to assure the proper amount of electrical contact. The other ends 45 of said springs are bent at right angles to the bifurcations and are secured to the shield by screws 33 and 34 and, in effect, act as the condensers C in the radio frequency shorting circuit. Although the condensers C offer an infinite impedance to the direct current being fed to the cathode filament, they offer a negligible impedance to the radio frequency, thereby effecting a tuning short circuit across the conductor lines 20, 21.
- 50 55 Preferably, there is also provided another contact spring 35, similar to those already described

and more clearly shown in Figs. 2 and 3, the upturned end of which is fastened directly to the inner periphery of the shield by a screw 36, the bifurcated end bearing upon the upper surface of the flange 10b of the slip bushing and surrounding in part the cylindrical portion 10a. This spring 35, however, is not insulated from the shield but makes a direct electrical connection to ground through the shield.

It can readily be seen that with this construction it is only necessary to insert a screw driver into the openings 37 and 38 in the shield 30 to adjust the set screws 24 and 25, thereby connecting or disconnecting the dual line conductors from the tube.

It will be apparent from the foregoing description that an effective short circuiting of the radio frequency is provided by bypassing the radio frequency from the conductors 20 and 21 to ground through the springs 31 and 32, the condensers C, and shielding 30, without causing any interference to the heating current being supplied to the filament of the cathode 2. It will also be apparent that with this type of construction the short circuiting means can be brought to the extended ends of the filament at their juncture with the envelope, thus tuning the cathode to resonance at a frequency at which the cathode is substantially a quarter wavelength long. With this construction it has been found possible to tune an oscillator using a tube usually suitable for operation only at lower frequencies to operate at approximately 700 megacycles per second.

While I have disclosed my invention applied to vacuum tube filament tuning, it should be understood that it is not limited to this particular use. The principles of my invention apply to any circuit in which it is desired externally to tune a line substantially enclosed in any envelope to the highest radio frequency at which it can operate.

It will be clearly understood by those skilled in the art, that the apparatus shown and described herein is only illustrative of my invention and is not to be construed as a limitation on the scope of my invention as set forth in the objects and appended claims.

I claim:

1. A line connector system connecting a vacuum tube comprising an envelope and a two conductor line element having a pair of leads extending through and beyond said envelope to a two conductor shielded line, comprising means coupling together said leads and the conductors of said shielded line, conductive means conductively connected to respective leads externally of said envelope substantially at the point where said leads emerge from said vacuum tube envelope and positioned adjacent the shield of said shielded line but insulated therefrom and forming a condenser therewith whereby an effective short circuit at the operating radio frequency is provided across said leads to tune said line element.

2. A cathode line connector system having means for tuning a cathode filament to a high radio frequency comprising a vacuum tube envelope, a cathode filament in said envelope having a pair of filament leads extending through and beyond said envelope, a two conductor shielded line, means coupling together said cathode filament leads and the conductors of said two conductor line, condenser means coupled between respective leads of said filament and the shield of said shielded conductor line, said condenser

means comprising connectors connected to said leads substantially at the point where said filament leads emerge from said vacuum tube envelope and positioned adjacent to portions of the shield of said line, and means insulating said connectors from said shield, said connectors, said insulating means and said adjacent shield portions forming low impedance radio frequency condensers whereby an effective short circuit at the operating radio frequency is provided across said filament leads.

3. A cathode line connector system according to claim 2, further comprising a third cathode filament lead extending through and beyond the seal of said envelope, a slip bushing having slotted cylindrical portions and a flanged base of greater diameter than the cylindrical portion, said bushing being positioned upon said third filament lead, a contact spring bifurcated at one end bent at right angles to the bifurcation at the other, fastened directly to the inner periphery of the shield of said shielded conductor line thereby connecting the filament directly to ground.

4. A cathode line connector system adapted for use with ultra high frequency circuits and including means for tuning a cathode filament to an operating frequency at which the filament is substantially a quarter wavelength, said means comprising a vacuum tube envelope, a cathode filament having three filament leads mounted within and extending through and beyond said envelope to supply heating energy to said filament, a two-conductor shielded line, means coupling together said cathode leads and the two conductors of said shielded line and the shield substantially at a point where said filament leads emerge from said envelope contact means connecting said leads to the shield of said line, the ends of said contact means adjacent said shield being mechanically connected to said shield, and means insulating at least one of said contact means from said shield, said insulating means, said insulated contact means and said shield forming a low impedance condenser at the operating frequency.

5. A cathode line connector system according to claim 4, wherein one filament lead is connected to substantially a midpoint of the filament and the contact means for said midpoint connected lead is conductively connected to said shield.

6. A line connector system for connecting a vacuum tube comprising an envelope and a two conductor line element having a pair of leads extending through and beyond said envelope to a two conductor shielded line, comprising slip bushings each provided with a slotted cylindrical portion and having a flanged base of greater diameter than the cylindrical portion, positioned upon each of said leads, a cylindrical coupling joined to each of the conductors of the shielded line adjacent said slip bushings, means on said coupling whereby each of said couplings and its associated slip bushing and lead may be secured together, and condenser means coupled between respective leads externally of said envelope and the shield of said shielded conductor line substantially at the point where said leads emerge from said vacuum tube envelope whereby an effective short circuit at the operating radio frequency is provided across said leads to tune said line element.

7. A line connector system for connecting a vacuum tube comprising an envelope and a two conductor line element having a pair of leads extending through and beyond said envelope to a

two-conductor shielded line, comprising slip bushings, each provided with a slotted cylindrical portion and having a flanged base of greater diameter than the cylindrical portion, positioned upon and conductively connected to each of said leads, a cylindrical coupling conductively joined to each of the conductors of the shielded line adjacent said slip bushings and conductively connected to said slip bushings, and condenser means coupled between respective leads external of said envelope and the shield of said shielded conductor line substantially at the point where said leads emerge from said vacuum tube envelope whereby an effective short circuit at the operating radio frequency is provided across said leads to tune said line element.

8. A cathode line connector system having means for tuning a cathode filament to a high radio frequency comprising a vacuum tube envelope, a cathode filament in said envelope having a pair of filament leads extending through and beyond said envelope, a two-conductor shielded line, means coupling together said cathode filament leads and the conductors of said two-conductor line, and condenser means coupled between respective leads of said filament and the shield of said shielded conductor line substantially at the point where said filament leads emerge from said vacuum tube envelope, said condenser means comprising a contact spring bifurcated at one end and bent at right angles to the bifurcation at the other, insulated from and fastened to the shield of said shielded conductor line and adapted to pass radio frequency current to ground, whereby an effective short circuit at the operating radio frequency is provided across said filament leads.

9. An electron tube system comprising an electron tube having an envelope, electrodes within said envelope and electrode leads extending through said envelope, a line comprising at least two conductors and forming with at least two of said leads a resonant circuit, and connectors connecting said conductors to said leads substantially at the point at which the leads emerge from said envelope, at least one of said connectors comprising conductive means conductively connected to one of said leads substantially at the point where it emerges from said envelope and positioned adjacent to a portion of the conductor connected to another of said leads
- 10 and means insulating said conductive means from said last mentioned conductor, said conductive means, said insulating means and said conductor portion forming a condenser having a low impedance at the operating frequency of the system.
